UNITED STATES PATENT OFFICE.

ERNEST B. SELLEW, OF PAWTUCKET, RHODE ISLAND.

METAL-WORKING MACHINE.

Specification of Letters Patent. Patented Oct. 19, 1920.

1,356,020.

Application filed February 1, 1909. Serial No. 475,452.

To all whom it may concern:

Be it known that I, ERNEST B. SELLEW, of Pawtucket, in the county of Providence and State of Rhode Island, have invented certain new and useful Improvements in Metal-Working Machines; and I do hereby declare the following specification, taken in connection with the accompanying drawings, forming a part of the same, to be a full, clear, and exact description thereof.

One feature of the present invention consists in providing means whereby in a machine, in which the feeding movements of the turret-slide are derived from the spindle operating mechanism, two different speeds may be given to the spindle in one direction and the spindle be rotated in the reverse direction, the change of speed of the spindle and the reversal of the spindle being automatically effected and the spindle being at all times operated, and consequently the feeding movements of the turret-slide derived, from a single constant speed driving member.

A further feature of invention consists in providing means whereby, when the direction of the spindle is reversed, the direction of rotation of the cam-drum which actuates the turret-slide, although driven from the spindle, will not be reversed, but will instead be always in the same direction.

A further feature of invention consists in providing means whereby the turret-slide and the cross-slide may be simultaneously adjusted, and so that the proper relation between these parts in any adjusted position will always be maintained.

A further feature of invention consists in providing means whereby the adjustment of the turret-slide, the adjustment of the cross-slide and the adjustment of the cross-slide mechanism, which latter adjustment is incidental to the adjustment of the cross-slide, may all be simultaneously effected by a single operation.

A further feature of invention consists in providing means whereby when the turret-slide is adjusted the devices for indexing the turret will be correspondingly and simultaneously adjusted, and so that said indexing devices will be in the proper position to index the turret at the end of the retracting movement of the turret, whatever the adjustment of the turret-slide may be.

A further feature of invention consists in providing means whereby the cross-slide

may be operated from the cam-drum by devices reciprocating in a direction lengthwise of the machine.

A further feature of invention consists in providing means whereby a facing tool arranged axially of the spindle will be advanced and retracted under the control of the advancing and retracting movements of the turret-slide.

The invention further consists in combinations and arrangements of parts herein-after described and claimed.

Referring to the drawings, Figure 1 is a central longitudinal section of the machine, 70 but showing the centrally arranged shafts and gears in full.

Fig. 2 is an end view of the machine with the gear-box cover removed.

Fig. 3 is a side elevation on an enlarged scale of the spindle end of the machine with the front of the easing removed.

Fig. 4 is a vertical section on the line 4-4 of Fig. 5 looking toward the turret end of the machine.

Fig. 5 is a central longitudinal section of the spindle end of the machine showing the construction and arrangement of the shafts, clutches, etc.

Fig. 6 is a vertical section on the line 6-6 of Fig. 5.

Fig. 7 is a vertical section on the line 7-7 of Fig. 5.

Fig. 8 is a horizontal section through the spindle-head on the line 8-8 of Fig. 4.

Fig. 9 is a corresponding horizontal section on the line 9-9 of Fig. 4.

Fig. 10 is a vertical section through the spindle-head on the line 10-10 of Fig. 5.

Fig. 11 is a vertical section on the line 11-11 of Fig. 1 looking toward the spindle end of the machine.

Fig. 12 is a central longitudinal section on an enlarged scale of the turret-slide and a portion of the cam-drum and connecting mechanism.

Figs. 13 to 26 inclusive are details showing different features of construction.

Figs. 27 and 28 are detail views of the dogs or cams.

Fig. 12 represents the frame or bed of the machine which is supported on suitable standards 13, 13. The work-spindle 14, which is shown as a hollow spindle, is mounted in suitable bearings and provided with the usual chuck 15. Mounted on the spindle is a single faced pulley 16 provided with an

105

110

elongated hub 17, on the end of which hub is formed a pinion 18. The pinion 18 meshes with a gear 19, the elongated hub 20 of which is suitably mounted in the frame.

Mounted in suitable bearings in the frame and in the hub 20 respectively is a short shaft 21. The shaft 21 is adapted to be connected with the gear 19 by means of the 10 double sliding clutch 22 to be hereafter referred to, and is so connected when the spindle is to be rotated in the forward direction. Secured to the outer end of the shaft 21 are two change gears 23 and 24 of different diameters. The gear 23 meshes with the gear 25 on a shaft 26, while the gear 24 meshes with the gear 27 on a shaft 28, Figs. 2 and 8. Loosely mounted on the shaft 26 is a gear 29 adapted to be connected 20 to said shaft by a sliding clutch 30 keyed to said shaft. The gear 29 meshes with the gear 31 connected to a short shaft 32. At the end of said shaft 32 is a gear 33 which meshes with a peripheral gear 34 secured to or formed integral with the chuck 15.

Secured to the shaft 28 is a gear 35 which meshes with a gear 36 which is adapted to be connected to or disconnected from the gear 31 by a reversible intermediate roller ratchet connection. The construction of this reversible roller ratchet connection which, in connection with the reversal of the spindle, constitutes a feature of the present invention, will be more fully described in connection with the description of the mechanism for reversing the spindle. So far as the rotation of the spindle at two different speeds in the forward direction is concerned, 40 the operation of the mechanism above described is as follows:

When the clutch 30 is shifted to engage the gear 29 with the shaft 26 motion will be imparted to the spindle 14 from the pulley 16 through gears 18, 19, shaft 21, gears 23, 25, shaft 26, gears 29, 31, shaft 32, and gears 33, 34. With the arrangement of gears shown this train of gearing will serve to impart a fast speed to the spindle, and 50 it will be understood that while the spindle is thus being rotated at the high speed by said gear 31 the speed of the shaft 32 will be such that, although the gear 36 is at the same time being rotated, said gear 36 will, 55 by reason of its slower speed and by reason of the roller ratchet connection above referred to, have no effect upon the shaft 32 which will be at this time rotated at a higher speed than said gear 36.

60 When now a slow speed is to be imparted to the spindle in the same direction, the clutch 30 is shifted to disconnect the gear 29 from the shaft 26, whereby said gear 29 and the gear 31 meshing therewith will be 65 caused to rotate idly. As above stated, the

gear 36 is in constant rotation, said gear being rotated from the shaft 21 through gears 24, 27, shaft 28 and gear 35. When, therefore, the gear 31 is by the shifting of the clutch 30 caused to rotate idly, the gear 36 will, through the roller ratchet connection referred to, pick up the shaft 32 and thereupon said shaft 32, and consequently the spindle 15, will thereafter be rotated by said gear 36 and at the slow speed. It 75 will be understood that by changing the gears 23, 24, together with the gears 25, 26, any desired speeds for the spindle may be provided for.

Referring now to the mechanism for reversing the spindle, the gear 19 meshes with a gear 37 (Fig. 8) secured to or formed integral with a sleeve 38 loosely mounted on the shaft 26. Secured to or formed integral with said sleeve is another gear 39 which meshes with a double gear 40 loosely mounted on a shaft 41 to be hereafter referred to. Also meshing with said double gear 40 is a gear 42 loosely mounted on the shaft 21 and adapted to be connected with said shaft by the double clutch member 22. By the train of gearing referred to the gear 42 is caused to rotate in a direction opposite to that of the gear 19 and at a greater speed. Consequently when the clutch 22 is shifted 90 to connect the gear 42 to the shaft 21 the spindle will be rotated in the reverse direction, the rotation of the spindle in such reverse direction being effected through the gear 31 or the gear 36 and the roller ratchet 95 connection above referred to and which will now be described.

Referring to Figs. 5, 17, and 18, there is secured to the shaft 32 a spider 43. The gear 31 is provided with one or more laterally projecting lugs 31^a, three of such lugs being shown in the drawings, and which lugs extend into the spaces between the arms of the spider 43, as shown in Fig. 18. Located one on each side of each of the lugs 31^a are two rollers 44 and 45, each of said rollers being arranged opposite or adjacent to a tangential inclined surface formed on the hub of the spider 43, as shown in Fig. 18. Preferably a spring-pressed plunger is 115 employed in connection with each of said rollers to facilitate the action thereof, but such plungers are not necessary.

With this construction, and assuming that for the forward rotation of the spindle the gears 31 and 36 are rotated in the direction of the arrow in Fig. 18, so long as the clutch 30 is in engagement with the gear 29, so as to positively drive the gear 31, the arm 31^a impinging against the roller 44 will force 120 said roller into the position shown in Fig. 18, and through the engagement of said roller with the arm of the spider 43 either directly or through the spring-pressed plunger, will directly impart rotation to 125 130

such spider, and thus to the shaft 32, and the spindle will be rotated at the fast speed. When now the clutch 30 is disconnected from the gear 29, and so that thereby the gear 31 becomes an idle gear, and thus no longer serves to rotate the spider 43, the roller 45 will as the gear 36 continues to revolve be forced up its incline, this movement being facilitated by the action of the spring-pressed plunger, and so that said roller 45 will be nipped between the gear 36 and the spider 43 and rotation of the spider and of the shaft 32 be then effected by the gear 36 through the engaging roller 45.

When now the rotation of the gears 31 and 36 is reversed, if the clutch 30 is in engagement with the gear 29 and the gear 31 thereby positively driven, then the lug 31^a will be caused to impinge against the roller 45 and through said roller acting against one of the arms of the spider 43 will cause said spider and the shaft 32 to be rotated in the opposite direction and at a fast speed. If, however, the clutch 30 be shifted to disconnect the gear 29, and so that the gear 31 becomes an idle gear, then the roll 44 will, by the rotation of the gear 36 assisted by its spring-pressed plunger, be forced up its incline, and so as to be nipped between the gear 36 and the spider 43 and thereby transmit rotation to the spider and the shaft 32 in the reverse direction, but at a slower speed.

Referring now to the mechanism for imparting feeding and return movements to the turret-slide, and first to the mechanism for imparting feeding movements thereto at different speeds, the rear end of the shaft 32 is provided with a pinion 46 which meshes with a gear 47 secured to or formed integral with a sleeve 48 loosely mounted on the shaft 28. Secured to or formed integral with said sleeve is another gear 49 which meshes with a gear 50 loosely mounted on the shaft 41 hereinbefore referred to, said gear 50 being adapted to be connected to and disconnected from said shaft 41 by the double clutch member 51 mounted on said shaft.

Secured to the outer end of the shaft 41 are two change gears 52 and 53. The gear 52 meshes with a gear 54 secured to a shaft 55, while the gear 53 meshes with a gear 56 secured to a shaft 57. Mounted on the inner end of the shaft 55 is a differential speed reducing gear box, designated as a whole at 58, of a well-known construction and which need not be described in detail. Loosely mounted on the shaft 55 adjacent to said gear box and operated therefrom is a gear 59. Mounted on the shaft 57 is a corresponding gear box 60 and a gear 61 operated therefrom. The gears 59 and 61 both mesh with a gear 62 secured to the cam-drum shaft 63. Two different speeds are

provided for by each of the gear boxes 58 and 60, and the reason for employing these two gear boxes with the two shafts 55 and 57 is to increase the number of speeds, four different speeds being provided for by the employment of the two gear boxes.

Means are provided which will be herein-after described for automatically effecting the desired changes in the two reducing speed gear boxes referred to.

Inasmuch as by the shifting of the clutch 22 the direction of rotation of the shaft 32 may be reversed for the purpose of reversing the spindle, it follows that, if the train of mechanism above described leading from the spindle operating train to impart feeding movements to the turret-slide were the only train provided for that purpose, the direction of rotation of the cam-drum shaft 63 would be reversed whenever the direction of rotation of the shaft 32 was reversed. It is not desired, however, that the direction of the cam-drum shaft and the cam-drum operated thereby shall be thus reversed, but instead it is desired that the cam-drum shall always rotate in the same direction. Consequently an additional train of mechanism with a shifting clutch is provided leading from the shaft 32 to the cam-drum shaft 63, whereby by the shifting of said clutch, when the direction of rotation of the shaft 32 is reversed, the shaft 63 will be operated by this second train of mechanism in the same direction as before. Loosely mounted on the shaft 41 is a gear 64 which also meshes with the pinion 46 on the shaft 32. This gear 64 is adapted to be connected with and disconnected from the shaft 41 by the double clutch member 51 before referred to. As will be seen, the gear 64 which, as above stated, meshes directly with the pinion 46, will thus be rotated in an opposite direction from the gear 50, which is rotated through the intermediate gears 47 and 49.

Means are provided for simultaneously shifting the two clutch members 22 and 51, such means comprising a lever 65 secured to a rock-shaft 66. It is preferred to make this lever 65 in the form of a double lever, as shown in Fig. 4, and so that each of the clutches will be thereby engaged on opposite sides. Means are provided for automatically rocking the shaft 66 and thus automatically shifting the clutches 22 and 51, which means will be hereafter described. It may, however, be here noted that with the construction above described, whenever the clutch 22 is shifted to reverse the spindle, thereby reversing the shaft 32, the clutch 51 will be simultaneously shifted, and so that when the shaft 32 is thus reversed the cam-drum shaft 63 will be operated from the shaft 32 through the gear 64, instead of through the gear 50, and so that the reversal of the shaft 32 will not effect

any corresponding reversal of the cam-drum shaft 63, but instead said cam-drum shaft will continue to be rotated in the same direction as before.

- 5 Referring now to the mechanism for imparting return movements to the turret-slide, it is to be understood that the return movements of said slide are to be at a constant speed and at a much greater speed 10 than the feeding movements thereof, and the mechanism to be described serves to impart return movements to the slide at such constant and higher speed.

As shown in Fig. 5, the hub 20 of the gear 19 is provided at its forward end with a gear or pinion 67 which meshes with a gear 68 loosely mounted on the shaft 32. This gear 68 constitutes one member of a friction clutch. Loosely mounted on the 20 shaft 32 adjacent to the gear clutch member 68 is a companion clutch member 69 which is likewise provided with gear teeth which mesh with the gear 62 secured to the cam-drum shaft 63. During the feeding movement 25 of the turret-slide the clutch members 68 and 69 are out of engagement with each other and each of said clutch members simply rotates loosely on the shaft 32. When, however, the return movement is to be imparted to the turret-slide, the clutch member 30 69 is automatically forced into engagement with the clutch member 68, and when this is done the gear 62, and consequently the cam-drum shaft 63, is rotated directly 35 from the gear 67 through the friction clutch referred to. It will be understood that as the speed of rotation thereby imparted to the cam-drum shaft 63 is much greater than the speed of either of the shafts 55 or 57, 40 the pawls in the reducing gear-box referred to will ride over the teeth of the gears in said box and so that the return movement may be imparted to the turret-slide through the friction clutch members 68, 69, without 45 in any way interfering with the train of mechanism for imparting feeding movements to said slide. The means for automatically controlling the engagement and disengagement of the clutch members 68 and 69 will 50 be hereafter described.

The turret end of the machine with the mechanism for actuating the turret-slide and the mechanism for actuating the cross-slide will next be described. The outer end 55 of the cam-drum shaft 63 is provided with a pinion 70 engaging an internal gear 71 on the cam-drum 72, said cam-drum being mounted to rotate on suitable bearings in the frame of the machine. The turret-slide 60 73 carrying the turret 74 is mounted to slide on the ways 75. Secured to the turret-slide, preferably near its rear end, is a block 76 carrying a roll 77 arranged to be engaged by the cams 78 on the cam-drum

72 for imparting the feeding and return movements to the turret-slide.

Mounted on the ways 75 and adapted to be adjusted longitudinally thereon is the base 79 provided with suitable ways for the cross-slide 80. In the present machine the 70 cross-slide is operated from the same cam-drum 72 which operates the turret-slide by means of a connecting device to which movements lengthwise of the machine are imparted by said cam-drum. Mounted to 75 slide in suitable ways formed on the frame of the machine is a sliding bar 81 located beneath the turret-slide. At its outer end this sliding bar 81 is provided with a roll 82 adapted to be engaged by cams 83 on 80 the cam-drum 72, by means of which cams reciprocating movements are imparted to said sliding bar.

The cross-slide 80 is provided on its under side with two angular slots 84, 85, extending transversely of the slide, which slots as shown in Fig. 22 come together at a common meeting point. The angular slots 84, 85, are adapted to be traversed, either the one or the other, by a roll 86, the movement of said roll in the slot 84 serving to move the cross-slide in one direction from a central position, and the movement of said roll in the slot 85 serving to move the cross-slide in the opposite direction from such 95 central position. So far as the main feature of the invention with respect to means for actuating the cross-slide is concerned, the roll 86 might be mounted directly on and carried by the sliding bar 81. For the 100 purpose of adjustment, however, as will be hereinafter more fully explained, said roll 86, instead of being mounted directly on the sliding bar 81, is mounted on a separate supplemental bar 87 which is adjustably connected to the bar 81. As shown in Fig. 12, the bar 81 is provided with an internal screw-thread forming an elongated semi-circular nut. Rotatably connected with the supplemental bar 87 is a screw 88 arranged 105 110 to engage the semi-circular nut formed on the interior of the bar 81.

It will be understood that the cross-slide is adapted and intended to be provided with a tool at each end thereof, one of said tools, 115 as for instance a tool for taking a roughing cut, being located on one side of the work held in the chuck, and the other tool, as for instance a tool for taking a finishing cut, being located on the other side of the work, 120 and the two angular slots 84, 85, are provided to actuate the cross-slide to bring first one and then the other of these tools into operative engagement with the work. If the cross-slide were provided with only one tool 125 located on one side of the work, only one angular slot would be required, and in such case the cross-slide would be moved first in

one direction and then in the other to advance and retract this tool by the travel of the roll 86 in such angular slot, first in one direction and then in the other.

5 When the cross-slide is provided with two tools and two angular slots are provided for advancing and retracting first one tool and then the other it is necessary to provide some means for directing the roll 86 first into one 10 of the two slots and then into the other. As shown in the drawings, a pivoted switch 89 is employed for this purpose, and means are provided for automatically operating this switch to direct the roll 86 first into the slot 15 84 and then into the slot 85. The switch 89 is pivoted at 90 and when said switch occupies the position shown in Fig. 22 the roll 86 will be directed into the slot 84, and when said switch is moved to its opposite position 20 said roll will be directed into the slot 85.

The switch 89 is provided with a spring-wire 91 which lies in a plane above the switch 89, one end of which wire is held in a slot formed in the hub 90 of the switch. 25 The other end of said wire projects beyond the end of the switch and extends into a slot 92 formed in the cross-slide base 79, as shown in Figs. 22 and 24. The ends of this slot are beveled and on the cross-slide there 30 is a plate 93 which at certain times will be caused to overlie the end of the spring-wire 91.

The operation of the mechanism for automatically operating the switch 89 is as follows: Assuming the parts to be in the 35 position shown in Figs. 22 and 24, as the roll 86 travels along the slot 84 the cross-slide will be moved to the right. In being thus moved to the right the plate 93 and the 40 free end of the spring-wire 91 will be moved with the cross-slide until said wire is brought into contact with the beveled end 94 of the slot 92, when said wire will be moved downward to the position indicated 45 in dotted lines in Fig. 24. At this time the movement of the cross-slide has not been entirely completed, but instead a further movement is imparted thereto corresponding substantially to the width of the plate 50 93, and so as to move said plate into the position indicated by dotted lines in Fig. 24, thereby carrying said plate from one side of the wire to the other. As soon as the plate in moving farther to the right has 55 passed by the wire, the wire which has been put under spring tension by its downward movement will spring up to the upper part of the slot and then on the return movement of the cross-slide the plate and wire will 60 move together. As will be understood, the shifting of the wire 91 from one side of the plate 93 to the other will effect a corresponding movement of the switch 89 by reason of the connection of the spring wire therewith, 65 and will thus move said switch to a position

to close the slot 84 and open the slot 85. As this movement of the switch takes place while the roll 86 is still in the slot 84, it is necessary that the roll shall be permitted to pass out of said slot. This is accomplished 70 by locating the wire above the switch 89 and thus above the top of the roll 86, and so that the roll may move the switch so as to enable it to pass out of the slot 84, said roll passing beneath the wire 91. As soon, 75 however, as the roll has passed out of said slot the switch will immediately, by the action of the spring wire, be thrown back to a position where it closes said slot 84 and opens the slot 85, and so that when the sliding bar 87 is next advanced the roll 86 will enter the slot 85 and thus move the cross-slide to the left or in a direction to advance the other tool thereon into operative engagement with the work. 80 85

As will be seen, the movement of the cross-slide, whether it be provided with only one tool and one angular slot for actuating said slide or whether provided with two tools and two angular slots, will be actuated by a 90 part or device which reciprocates lengthwise of the machine under the direct action of the cam-drum. It will also be seen that with the construction shown in which the roll 86 is caused at each reciprocation to traverse the 95 entire width of the cross-slide a comparatively long stroke is imparted to the cross-slide in either direction from its mid-position.

In order to enable the turret-tools to operate properly upon articles of work which project varying distances from the spindle-chuck it is customary in machines of this character to give to the turret-slide varying 100 lengths of stroke for the several indexed positions of the turret, according to the tools carried in the turret and the character of the work to be performed thereby, the several lengths of the stroke being automatically effected by the proper cams on 105 the cam-drum. In such cases, however, the end of the retracting stroke or beginning of the forward stroke of the turret is always at the same point for each reciprocation of the 110 turret-slide. 115

In addition to this automatic variation of the length of stroke of the turret-slide it is desirable to provide means for adjusting said turret-slide with relation to its operating cams, or in other words, to adjust or change the point at which the forward stroke commences and consequently the points at which the several forward strokes terminate, such adjustment being to accommodate pieces of work which project at 125 varying distances from the spindle-chuck. Where means are thus provided for adjusting the turret-slide with relation to its operating cams, it is also desirable to adjust 120 the position of the cross-slide, and so that 130

the proper relation between the cross-slide and the turret-slide may be maintained and to bring the cross-slide to a position where it will not interfere with the advancing movement of the turret-slide in its newly adjusted position. On the other hand it sometimes is desirable to adjust the position of the cross-slide by reason of the diameter of the work held in the chuck, that is, the cross-slide will ordinarily, when the work is of sufficiently small diameter, occupy a position beneath the projecting work. But when the work is of such a large diameter that the cross-slide cannot occupy this position, it becomes necessary to adjust the cross-slide so that it will be at a point beyond the end of the projecting work. When the cross-slide is so adjusted it is desirable that the turret-slide shall also be correspondingly adjusted in order to make certain that the cross-slide will not interfere with the advancing movement of the turret on its longest stroke.

In the present machine means are provided whereby the turret-slide and the cross-slide may both be simultaneously adjusted and by one operation, and this means will next be described.

Referring to Fig. 12, the block 76 which carries the roll 77 is adjustably secured to the turret-slide. The turret-slide is provided with an elongated slot 95 through which extends a stud 96 projecting from said block 76. The upper end of the stud 96 is screw-threaded to receive a clamp nut 97 by means of which the block 76 is clamped to the turret-slide in any of its different adjusted positions.

The block 76 is provided with a screw-threaded aperture extending therethrough, said block thus constituting a nut to coöperate with a hollow screw 98 which extends therethrough. The outer end of this hollow screw 98 is journaled in a lug 99 depending from the turret-slide. The hollow screw 98 is provided at its outer end with a squared hole 100 adapted to receive a socket-wrench for turning said screw by hand when desired. As will be seen, by loosening the clamp nut 97 and turning the hollow screw 98 the turret-slide will be adjusted lengthwise with relation to the block 76, or said block will be adjusted with relation to the turret-slide. With the parts in the position shown in the drawings the end of the screw 98 abuts against a part which at the time constitutes an abutment therefor, and with the parts in such position when the screw 98 is turned the turret-slide will be moved with relation to the block and the position of the turret-slide be thereby adjusted with relation to its operating cam.

Extending within the hollow screw 98 and splined thereto, and so as to be turned therewith, is a screw-rod 101. This rod 101

is journaled in a cross-bar 102 on the frame. A connecting bar 103 is secured at its inner end to the cross-slide base 79 and at its outer end is provided with a lug or projection 104 having a screw-threaded aperture through which the screw-threaded portion of the screw 101 extends. With this construction, as will be seen, when the hollow screw 98 is turned by the engagement of a wrench or other hand device therewith, the screw 101, being keyed to said hollow screw, will be turned therewith, and the turning of said screw 101 will, through its engagement with the projection 104, cause a movement to be imparted to the cross-slide base lengthwise of the frame corresponding to the movement imparted to the turret-slide. Thus with this construction by turning the hollow screw 98 both the turret-slide and the cross-slide will be simultaneously adjusted by a single operation and will always maintain the same relation to each other in any adjusted position.

By reason of the fact that the cross-slide 80 is operated by the longitudinally sliding bar 81, it is desirable, in order to provide for the adjustment of the cross-slide above referred to, to provide means whereby a corresponding adjustment will be made in the connection between the sliding bar 81 and the cross-slide 80. It is for this purpose that the supplemental bar 87 with the rotary screw 88 mounted therein is provided, said screw 88 engaging the half nut formed on the bar 81. For the purpose of turning said screw 88 the unthreaded end of the screw 101 is extended therethrough and splined thereto. Consequently when the hollow screw 98 is turned and the screw 101 is turned thereby, the hollow screw 88 will be turned by said screw 101, which will effect the proper adjustment between the sliding bar 81 and the supplemental bar 87, and so that whenever the cross-slide is adjusted the cross-slide mechanism and the distance between the roll 82 and the roll 86 will be correspondingly adjusted. As will be seen, this adjustment of the cross-slide mechanism will be effected simultaneously with the adjustment of the turret-slide and the cross-slide and by the same operation.

In the present machine the pawl 105, which engages the pins 106 on the turret 74 for indexing said turret, is mounted on the connecting bar 103 and pivoted thereto at 107. As will be seen, therefore, whenever the turret-slide is adjusted the position of the indexing pawl 105 will, by the adjustment of the connecting bar 103, be correspondingly adjusted, and so that the position of said indexing pawl will be likewise correspondingly adjusted for the adjusted position of the turret-slide, the adjustment of said indexing pawl being likewise ef-

fected simultaneously with and by the same operation by which the adjustment of the turret-slide, the cross-slide, and the cross-slide mechanism is effected.

5 As hereinbefore stated, means are provided whereby the speed of the spindle and the reversal of the spindle will be automatically effected at the desired times, and also whereby the speed of the advance or feeding movements of the turret-slide or cross-slide may be automatically varied, and also whereby the return movements of the turret at a constant speed may be automatically effected. The means for thus automatically effecting these several operations will next be described.

As hereinbefore explained, the change in the speed of the spindle from a fast speed to a slow speed or vice versa is effected by a shifting of the clutch 30. It remains, therefore, only to describe the mechanism for automatically shifting said clutch 30. Referring to Figs. 3 and 6, the clutch 30 is engaged by one end of a clutch-lever 108 pivoted to the frame at 109. The lower end of said clutch-shifting lever extends between two collars 110, 110, secured to a sliding rod 111. Said rod 111 is connected to a rock-arm 112 secured to a hollow rock-shaft 113. Secured to or formed integral with the rock-shaft 113 is a segment-gear 114, the teeth of which engage the teeth of a rack formed on a sliding bar 115 (Fig. 19). Projecting from the outer end of the rack-bar 115 is a pin 116 adapted to be engaged by a cam or dog A adjustably secured in a T-slot 117 on the periphery of the cam-drum 72. In Fig. 3 the clutch 30 is shown in engagement with the gear 29, at which time the spindle will be rotated at the fast speed. When the rack-bar 115 is actuated by the engagement of the pin 116 with the cam A, the rod 111 will be moved to throw the clutch 30 out of engagement with the gear 29 and the spindle will then be rotated at the slow speed. It will be understood that a corresponding dog or cam A' (Fig. 27) is to be secured in reverse position in the T-slot 117 for the purpose of shifting the rack-bar 115 in the opposite direction, thereby throwing the clutch 30 back into engagement with the gear 29 to change the spindle back to the fast speed.

Referring next to the mechanism for automatically reversing the spindle, this is effected, as above stated, by shifting the clutch 22. The shifting of this clutch 22 is effected by an extended movement of the rod 111. Referring to Fig. 3, the clutch 22 is operated by the clutch-shifting lever 65 secured to and operated by the rock-shaft 66. Secured to said rock-shaft is a downwardly extending arm 118, the lower end of which arm extends between two collars 119, 119, secured to said rod 111. As shown in Fig. 3,

the collars 119, 119, are spaced sufficiently apart to provide for a certain amount of lost motion between the end of the arm 118 and said collars, said lost motion being provided to permit the clutch shifting lever 108 to be moved to disengage the clutch 30 without imparting any movement to said arm 118 and thus without effecting any movement of the clutch 22. When it is desired that the arm 118 shall be moved to shift the clutch 22, a greater extent of movement is to be imparted to the rod 111, and this is automatically effected by providing a dog or cam A' (Fig. 27) secured in the T-slot 117 of the cam-drum, said cam A' being provided with a cam face of correspondingly greater length than the cam face of the dog

A. When, therefore, the pin 116 on the rack-bar 115 is engaged by said dog A' the rod 111 will be moved a sufficient distance to shift the clutch 22 and thereby reverse the spindle. It will be noted that by reason of the lost motion referred to, before the arm 118 is moved to shift said clutch 22, the clutch 30 will have been disengaged by the movement of its shifting lever 108.

As above explained, when the clutch 22 is shifted to reverse the spindle, the clutch 51 is simultaneously shifted to prevent the reversal of the cam-drum. It will be understood that at the time the clutches 22 and 51 are shifted the cam-drum is being operated by the independent train of mechanism by which return movements are imparted to the turret-slide. It will be further noted that if a dog or cam, such as A, be so located on the cam-drum as to cause the rod 111 to be moved while the cam-drum is being operated by the feeding train of mechanism that is being operated through the clutch 51, the result would be to stop the entire machine, because in such case both clutches 22 and 51 would be moved to mid-position, and as the rotation of the cam-drum will be thereby arrested there would be nothing to complete the shifting of said clutches.

Referring next to the means for automatically varying the speed of the cam-drum 72, and consequently the speed of the feeding movements of the turret-slide, as hereinbefore stated four different speeds are provided for by the employment of the two differential speed reducing gear boxes 58 and 60. The operation of the cam-drum shaft 63 through one or the other of said gear boxes and the speed at which said shaft will be rotated is automatically controlled by the movements of a rod 120. It will be understood that this rod is caused to occupy four different longitudinal positions, one for each of the four different speeds for the feeding movements of the turret. It will be further understood that the shifting of the rod 120 from one position to another effects a change of the speed through the action of the pins

- 121 and the pawls 122, Figs. 5 and 7, which coöperate with the internal gearing in the gear boxes 58 and 60, respectively. Three of the four different speeds referred to are 5 provided for by the three different pins 121 with their coöoperating pawls 122, while the fourth and slowest speed is provided for by a permanent connection in one of the gear boxes.
- 10 Referring now to the means for giving the different positions to the rod 120, said rod is provided at its outer end with rack-teeth which engage a pinion 123 on a transverse shaft 124 mounted in suitable bearings. Said shaft 124 is provided at its other end with a pinion 125 which engages rack-teeth on a sliding bar 126. The outer end of said rack-bar 126 is beveled on opposite sides and is adapted to be engaged by a dog 15 or cam C secured in a cam-slot 127 in the cam-drum. Said rack-bar 126 is also provided at its outer end and on its upper surface with a series of stops or shoulders 128, three in number. Pivoted to the frame, or 20 to a cover which is bolted to the frame, is a swinging lever 129 which is adapted to engage one or the other of the shoulders 128 according to the position of the rack-bar 126. It will be understood that for the four 25 speeds referred to there will be four dogs or cams C around the periphery of the cam-drum, and that these several dogs, which are adjustable, will be adjusted to different positions so that the rack-bar 126, and consequently the rod 120, will be moved by said dogs in turn to four different positions. It 30 will be further understood that as said rack-bar 126 is moved to one position or the other the swinging lever 129 will engage one or 35 the other of the shoulders 128, and thus hold said rack-bar in the position to which it has been moved by the dog which actuates the same.
- For the purpose of tripping the lever or 40 latch 129 when desired another series of cams B, secured in the T-slot 130 formed in the cam-drum, are provided. Each of these cams B is adjustable radially as well as peripherally. The lever or latch 129 is secured 45 to a rock-shaft 131 mounted in a bracket 132 secured to the frame. To the opposite end of said rock-shaft 131 is secured an arm or lever 133, the end of which lies in the path of the dogs or cams B. By adjusting 50 the several dogs or cams B radially the rock-shaft 131, and consequently the lever 129, will be moved outward a greater or less distance, as desired, and so as to permit the movement of the rack-bar 126 a distance 55 from one step 128 to another, or any other desired distance within the range of movement of said rack-bar. As shown in Fig. 1 the spiral spring 134 surrounds the outer end of the rod 120, said spring abutting 60 against a collar 135 secured to said rod and

at the other end against a fixed abutment 136.

As shown in Fig. 11, it will be seen that the rod 120 and the rack-bar 126 are arranged on opposite sides of the transverse shaft 124, and so that the movements of said rod 120 and rack-bar 126 are in opposite directions, or in other words, when the rack-bar 126 is moved to the left in Fig. 19, the rod 120 will be moved to the right in Fig. 1. As will be further seen, when said rod 120 is moved to the right in Fig. 1 the spring 134 will be compressed, and so that, when the rack-bar 126 is free to move, said spring will serve to move the rod 120 and 80 rack-bar 126 in the opposite direction.

As will be seen, by a proper arrangement and adjustment of the cams C and B on the cam-drum, the rod 120 will be automatically moved into any one of its four positions to give to the cam-drum a rotation at any one of the four different speeds for imparting feeding movements to the turret-slide.

As hereinbefore stated, the return movements of the turret-slide are effected by a separate train of mechanism, and at a constant fast speed as compared with the feeding movements thereof. The operation of this separate return train of mechanism for 90 imparting the return movements to the turret-slide is controlled by the clutch 68, 69, that is, when the return movement of the turret is to be effected the clutch-member 69 is to be moved into engagement with the 95 clutch member 68. This engagement of said clutch-members is likewise automatically effected by the movement of the rod 120. As shown in Fig. 5, the inner end of said rod 120 abuts against the lower end of a swinging lever 137 pivoted to the frame at 138, which swinging lever, as shown in Figs. 5 and 6, surrounds the shafts 32 and 63. The hub of the clutch member 69 is provided at its outer end with a thrust collar 139 against 100 which the swinging lever 137 bears, as shown in Fig. 5. With this construction, as will be seen, when the rod 120 is free to be thrown to the left in Fig. 1 by the spring 134, the movement of said rod under the 105 action of said spring will, through the swinging lever 137 and thrust collar 139, serve to move the clutch member 69 into engagement with the clutch member 68, and thus start up the train of mechanism for 110 imparting the fast return movements to the turret-slide. As will be understood, in order for the rod 120 to be thus free to be actuated by the spring 134, it is necessary that one of the dogs B shall operate to raise the latch-lever 129 sufficiently high to disengage all 115 of the stops 128 and thus completely release the rack-bar 126.

It will be seen that the position of the rod 120 which determines the speed of the 130

cam-drum for the feeding movements of the turret-slide is regulated or controlled by two sets of cams on the cam-drum in connection with a spring for actuating said rod in one direction and a latch adapted to engage one or the other of a series of steps on the rack-bar 126, which latch thereby serves to hold the rod 120 against the action of said spring in any one of its adjusted positions corresponding to the steps on said rack-bar.

It will be further seen that the two sets of cams referred to are mounted in two separate slots on the cam-drum and thus may, if desired, be adjusted in close relation to each other or even directly in line with each other, as shown in Fig. 19.

There remains to be described the feature which consists in providing means whereby a facing tool arranged axially of the spindle 20 may be advanced and retracted in unison with the advancing and retracting movements of the turret-slide.

Referring to Fig. 1, the facing tool 140 is carried by a shaft 141 which extends axially through the hollow spindle 14. Pivoted to a bracket 142 secured to the frame is a lever 143, one end of which lever is pivotally connected to the outer end of the shaft 141 and the other end of which lever is pivotally connected to an adjustable nut 144. Preferably each end of said lever is forked to engage the end of the shaft 141 and the nut 144, respectively, on opposite sides thereof. The nut 144 engages a screw-threaded portion of a sliding rod 145 which is mounted to slide in a bearing 146 on the frame. Secured to the rod 145 is a collar 147, and arranged between this collar and the end of the bearing 146 is a spiral spring 148 surrounding the rod 145. Secured to said rod 145 on the opposite side of said bearing is another collar 149. Mounted on and secured to the top of the turret 74 is an arm or upward projection 150, and this arm 45 or projection 150 is so mounted on the turret that in one of the indexed positions of the turret the top of said arm will be in line with the sliding rod 145, but in the other indexed positions of the turret, will be out of 50 line with said rod.

The operation of this facing tool mechanism will be readily understood. As the turret-slide advances when the turret is in the indexed position, which brings the arm 55 150 in line with the sliding rod 145, said arm 150 will be caused to engage the end of the sliding rod 145, and then as the turret-slide continues to advance, will operate to move said rod to the left in Fig. 1, which 60 movement through the lever connection will serve to move the shaft 141 and the facing tool carried thereby to the right and thus into operative engagement with the work held in the chuck 15, the continued advance 65 of the turret-slide serving to give a cor-

responding feeding movement to the facing tool in its operation upon the work. By turning the rod 145 in the nut 144 the position of the forward end of said rod may be adjusted to cause the proper feeding movement to be given to the facing tool, according to the work to be done thereby. When the turret-slide is retracted the spring 148, which has been compressed during the movement of the rod 145 referred to will 75 operate to return said rod to its normal position.

As the work operated upon by the facing tool 140 is being rotated it is necessary that said facing tool and its shaft shall be held 80 against rotation while in engagement with the work, and said facing tool and its shaft are so held against rotation by the lever 143 through which the advancing movement is imparted to said shaft.

It is desirable when the last tool has operated and the work has been completed that the machine shall be automatically stopped. This may be accomplished by so locating a dog A on the cam-drum that the clutches 90 22 and 51 will be actuated while the cam-drum is being operated by the feeding train, which will result in said clutches being moved to mid-position, thereby stopping not only the movements of the turret-slide, 95 but also the rotation of the spindle. Preferably the parts are arranged so that, after the last tool has operated, the turret-slide will be retracted, and the turret indexed, and so that a feeding movement of the turret-slide will then be commenced at a slow speed for the purpose of causing said clutches 22 and 51 to be thus moved to mid-position.

What I claim as my invention and desire 105 to secure by Letters Patent is:

1. The combination, with the work-spindle and the tool-slide, of a driving member, mechanism connecting said driving member to said spindle, mechanism operated from 110 said spindle-operating mechanism for imparting feeding movements to said tool-slide, means for changing the speed of said spindle and correspondingly changing the speed of the feeding movements of said tool-slide, means for reversing the rotation of said spindle, and means for changing the speed of the feeding movements of said tool-slide independent of the speed of the spindle.

2. The combination, with the work-spindle and the tool slide coöperating therewith, of a driving member, and mechanism connecting said driving member to said spindle and adapted to rotate said spindle in both 125 directions at one or the other of two different speeds, said mechanism embodying a shaft, two gears on said shaft, one secured thereto and the other loose thereon, and a ratchet connection between said gears.

3. The combination, with the work-spindle and the tool slide coöperating therewith, of a driving member, and mechanism connecting said driving member to said spindle and adapted to rotate said spindle in both directions at one or the other of two different speeds, said mechanism embodying a shaft, two gears on said shaft, one secured thereto and the other loose thereon, a ratchet connection between said gears, and means for rotating one of said gears at a faster speed than the other. 70
4. The combination, with the work-spindle and the tool slide coöperating therewith, of a driving member, and mechanism connecting said driving member to said spindle and adapted to rotate said spindle in both directions at one or the other of two different speeds, said mechanism embodying a shaft, two gears on said shaft, one secured thereto and the other loose thereon, with a reversible ratchet connection between them, means for rotating the loose gear at a relatively slow speed, means for alternately connecting the other gear to and disconnecting it from said driving member, and means for reversing the rotation of said gears. 75
5. The combination, with the work-spindle and the tool slide coöperating therewith, of a driving member, and mechanism connecting said driving member to said spindle, said mechanism embodying a shaft, two gears on said shaft, one secured thereto and the other loose thereon, with a reversible ratchet connection between them, means for rotating the loose gear continuously in either direction at a relatively slow speed, means for intermittently rotating the other gear in either direction at a higher speed, and means for reversing the rotation of said gears. 80
6. The combination, with the work-spindle and the tool slide coöperating therewith, of a driving member, and mechanism connecting said driving member to said spindle, said mechanism embodying two gears adapted to be rotated at different speeds, means for reversing the rotation of said gears, and a reversible ratchet connection between said gears. 85
7. The combination, with the work-spindle and the tool slide coöperating therewith, of a driving member, and mechanism connecting said driving member to said spindle, said mechanism embodying a shaft, two gears on said shaft, one gear being loose on said shaft and adapted to be continuously rotated at a relatively slow speed and the other gear adapted to be intermittently rotated at a higher speed, means for reversing the rotation of said gears, and a reversible ratchet connection between said gears. 90
8. The combination, with the work-spindle and the tool slide coöperating therewith, of a driving member, mechanism connecting said driving member to said spindle, said mechanism embodying a shaft, two gears on said shaft, one secured thereto and the other loose thereon, with a ratchet connection be- 95
- tween them, means for continuously rotating the loose gear at a relatively slow speed, and means for alternately connecting the other gear to and disconnecting it from said driving member. 100
9. The combination, with the work-spindle and the tool slide coöperating therewith, of a driving member, mechanism connecting said driving member to said spindle, said mechanism embodying a shaft, two gears on said shaft, one secured thereto and the other loose thereon, with a reversible ratchet connection between them, means for rotating the loose gear at a relatively slow speed, means for alternately connecting the other gear to and disconnecting it from said driving member, and means for reversing the rotation of said gears. 105
10. The combination, with the work-spindle and the tool slide coöperating therewith, of a driving member, mechanism connecting said driving member to said spindle, said mechanism embodying a shaft, two gears on said shaft, one secured thereto and the other loose thereon, with a reversible ratchet connection between them, means for rotating the loose gear continuously in either direction at a relatively slow speed, means for intermittently rotating the other gear in either direction at a higher speed, and means for reversing the rotation of said gears. 110
11. The combination, with the work-spindle and the cam-drum for operating the tool-slide, of a driving member, mechanism connecting said driving member to said spindle, mechanism operated from said spindle-operating mechanism for rotating said cam-drum, and means operated from said driving member for reversing the rotation of said spindle without reversing the rotation of said cam-drum. 115
12. The combination, with the work-spindle and the cam-drum for operating the tool-slide, of a driving member, mechanism connecting said driving member to said spindle, two trains of mechanism operated from said spindle-operating mechanism for rotating said cam-drum, a clutch for reversing the rotation of the spindle, a second clutch for causing the cam-drum to be operated by one or the other of said two trains of mechanism, and means for simultaneously shifting said clutches. 120
13. The combination, with the work-spindle and tool-slide, of a driving member, mechanism connecting said driving member to said spindle, mechanism operated from said spindle-operating mechanism for imparting feeding movements to said tool-slide, means for varying the speed of said feeding movements independent of the speed of the spindle, said means embodying two shafts, each provided with a speed gear-box. 125
14. The combination, with the work-spindle and the cam-drum for operating the tool-slide, of a driving member, mechanism connecting said driving member to said spindle, said mechanism embodying a shaft, two gears on said shaft, one secured thereto and the other loose thereon, with a ratchet connection be- 130

5 tool-slide, of a driving member, mechanism connecting said driving member to said spindle, mechanism operated from said spindle-operating mechanism for rotating said cam-drum to impart feeding movements to said tool-slide, means for varying the speed of said cam-drum, said means embodying two shafts each provided with a speed gear-box and both connected to said 10 cam-drum.

15 15. The combination of a cross-slide, longitudinally movable means for operating said cross-slide, and a cam-drum provided with adjustable cams for actuating said longitudinally movable means.

20 16. The combination of a turret-slide, a cross-slide, longitudinally movable means for operating said cross-slide, and a cam-drum provided with adjustable cams for actuating both said turret-slide and said 25 cross-slide operating means.

25 17. The combination of a turret-slide, a cross-slide, and common means for simultaneously adjusting both said turret-slide and said 30 cross-slide.

30 18. The combination of a turret-slide, a cross-slide, means for operating said cross-slide, and common means for simultaneously adjusting said turret-slide, said cross-slide and said cross-slide mechanism.

35 19. The combination of a turret-slide, a means for indexing said turret-slide, a cross-slide, means for operating said cross-slide, and common means for simultaneously adjusting said turret-slide, said indexing mechanism, said cross-slide and said 40 cross-slide mechanism.

40 20. The combination of a cross-slide provided with two angular slots, and a longitudinally movable bar having a projection adapted to travel in either of said angular 45 slots.

45 21. The combination of a cross-slide provided with two angular slots, a longitudinally movable bar having a projection adapted to travel in either of said slots, and a switch for guiding said projection into the one slot or the other.

50 22. The combination of a cross-slide provided with two angular slots, a longitudinally movable bar having a projection adapted to travel in either of said slots, and a switch adapted to automatically guide said projection first into one slot 55 and then into the other to actuate said cross-slide first in one direction and then in the other.

55 23. The combination of a cross-slide provided with two angular slots, each extending substantially the entire width of said cross-slide, a longitudinally movable bar having a projection adapted to travel in either of said slots, and means for moving said bar first in one direction and then

60 in the other for a distance substantially equal to the width of said cross-slide.

65 24. The combination, with the work-spindle and the tool-slide, of a cam-drum provided with cams for actuating said tool-slide and also with cams for effecting a variation in the speed of the spindle and for effecting a reversal of said spindle.

70 25. The combination, with the tool-slide, of means for imparting feeding movements to said tool-slide, means for varying the speed of said feeding movements, and a cam-drum provided with cams for actuating said tool-slide and also with cams for effecting a variation in the speed of the feeding movements of said tool-slide.

75 26. The combination, with the tool-slide, of means for imparting feeding movements to said tool-slide, means for providing different speeds for said feeding movements, a cam-drum provided with cams for changing the speed of said feeding movements, and also with cams for determining which of said different speeds is to be employed.

80 27. The combination, with the tool-slide, of means for imparting feeding movements to said tool-slide, means for providing different speeds for said feeding movements, a cam-drum provided with cams for actuating said tool-slide, and also with cams for changing the speed of said feeding movements and with cams for determining which of said different speeds is to be employed.

85 28. The combination, with the work-spindle and the tool-slide, of means embodying a clutch for changing the speed of said spindle, a rod for shifting said clutch to change the speed of the spindle, a cam-drum provided with cams for actuating said tool-slide and also with cams for actuating said clutch-shifting rod.

90 29. The combination, with the work-spindle and the tool slide coöperating therewith, of means embodying a clutch for changing the speed of said spindle, means embodying a clutch for reversing the rotation of said spindle, a rod adapted to shift said speed-changing clutch, and adapted by a further movement thereof to shift said reversing clutch.

95 30. The combination, with the work-spindle and the tool slide coöperating therewith, of means embodying a clutch for changing the speed of said spindle, means embodying a clutch for reversing the rotation of said spindle, a rod adapted to shift said speed-changing clutch and adapted by a further movement thereof to shift said reversing clutch, and a cam-drum provided with a cam to actuate said rod to shift said speed clutch and also with a cam to further actuate said rod to shift said reversing clutch.

100 31. The combination, with a hollow work-

- spindle and a tool-slide, of a tool-spindle extending through said hollow spindle and adapted to carry a suitable tool, and means actuated by said tool-slide for advancing 5 said tool-spindle to bring the tool carried thereby into engagement with the work held in said work-spindle.
32. The combination, with a hollow work-spindle and a tool-slide, of a tool-spindle 10 extending through said hollow spindle and adapted to carry a suitable tool, and a sliding rod connected with said tool-spindle and having its end in the path of said tool-slide.
33. The combination, with a hollow work-spindle and a turret-slide and turret, of a 15 tool-spindle extending through said hollow spindle, a sliding rod connected to said tool-spindle, and a projection on said turret adapted in one of the indexed positions of 20 said turret to be brought in line with said sliding rod.
34. A metal-working machine comprising a constant speed driving shaft, a work spindle, a tool-carrier-reciprocating drum, a 25 feed shaft operatively connected with said drum, variable speed power-transmitting mechanism for forwardly driving said spindle and said feed shaft together and at different working speeds, means for reversing 30 the direction of rotation of said spindle, and independent power-transmitting mechanism actuated by said constant speed driving shaft for forwardly driving said feed shaft when the spindle is being driven in a reverse 35 direction.
35. A metal-working machine comprising a constant speed driving shaft, a work spindle, a tool-carrier-reciprocating drum, a feed shaft operatively connected with said 40 drum, variable speed power-transmitting mechanism for forwardly driving said spindle and said feed-shaft together and at different working speeds, means for reversing the direction of rotation of said spindle, and 45 independent variable speed power-transmitting mechanism actuated by said constant speed driving shaft for driving said feed shaft forwardly at different speeds when the spindle is being driven backwardly or in a 50 reverse direction.
36. A metal-working machine comprising a constant speed driving shaft, a work spindle, a tool-carrier-reciprocating drum, a feed shaft operatively connected with said 55 drum, variable speed power-transmitting mechanism for forwardly driving said spindle and said feed shaft together and at different working speeds, means for reversing the direction of rotation of said spindle, and 60 independent variable speed power-transmitting mechanism actuated by said constant speed driving shaft for driving said feed shaft forwardly at different speeds when the spindle is being driven backwardly, and
- mechanism operated by said feed shaft for 65 automatically controlling said variable speed power-transmitting mechanisms and said reversing means.
37. In a metal-working machine, the combination with a main frame, and a work 70 spindle and a feed shaft for feeding the tools, both mounted thereon, of a constant speed drive shaft, power-transmitting connections operated by the drive shaft for rotating said feed shaft independently of the 75 spindle, variable speed-power-transmitting mechanism operated by said constant speed drive shaft for driving said spindle and speed shaft together at different working speeds, including means for reversing the 80 direction of rotation of said spindle at said different speeds, and means for automatically disconnecting said feed-shaft from said variable speed power-transmitting mechanism when the direction of rotation 85 of said spindle is reversed.
38. The combination with the work spindle, the tool-slide and the cam-drum for operating the tool-slide, of a driving member operating at a constant speed in one direction, an idle connection from said driving-member to said cam-drum for operating 90 said tool-slide at fast speed when tools are idle and a working connection from said driving-member through said work-spindle 95 to said cam-drum for rotating said work-spindle and operating said tool-slide during the working movement of the tools, said working connection comprising means to drive the work-spindle reversibly through 100 different trains of gearing each including separate speed-changing means, mechanism for automatically changing the drive in said connection from one train of gearing to another including the connection between the 105 work-spindle and cam-drum including different trains of gearing, each train including separate speed changing means and means for automatically changing from one 110 of said trains of gearing to another for automatically changing the speed of the cam-drum, mechanism in the connection between the driving member and the work-spindle for reversing the direction of rotation of the work-spindle and another reversing 115 mechanism in the connection between the work-spindle and the cam-drum, means connecting one reversing mechanism to the other to maintain the forward rotation of the cam-drum and means for automatically 120 changing the drive of the cam-drum from the idle connection to the working connection.
